ATTORNEYS

UNITED STATES PATENT OFFICE.

GEORGE E. POWERS, OF WILBERFORCE, OHIO.

RIM-SPREADER.

1,121,396.

Specification of Letters Patent. Patented Dec. 15, 1914.

Application filed January 20, 1914. Serial No. 813,301.

To all whom it may concern:

Be it known that I, GEORGE E. POWERS, a citizen of the United States, and a resident of Wilberforce, in the county of Greene and State of Ohio, have made certain new and useful Improvements in Rim-Spreaders, of which the following is a specification.

This invention relates to wheelwrights' tools, and more particularly to a tool for spreading or drawing the rim of a wheel during the operation of attaching the rim to the spokes.

One of the principal objects of the invention is to provide a tool which may be clamped to the ends of a half rim, and operated to spread the rim or draw it as desired, in order to facilitate the adjustment of the rim to the wheel spokes.

Another object of the invention is to provide a device of the class described which will be simple, durable, efficient in operation and inexpensive to manufacture.

With these and other objects in view, which will become apparent as the description proceeds, the invention resides in the construction, combination, and arrangement of parts, hereinafter more fully described and claimed, and illustrated in the accompanying drawings, in which like characters of reference indicate like parts in the figures, of which,

Figure 1 represents a perspective view of the device, showing the same as attached to a half rim, the latter being shown in dotted lines, Fig. 2 represents a horizontal sectional view taken on the plane indicated by the broken line 2—2 of Fig. 1, and, Fig. 3 represents a fragmentary perspective view showing means whereby the device may be adjusted.

In carrying out one embodiment of the invention, there is provided a pair of substantially arcuate arms 5, oppositely disposed, to form approximately a half circumference, and flattened at their adjacent ends, as at 6, to provide eyes, and the arms are pivotally connected by means of a pin or bolt 7 projecting through eyes 6, and on one end of which is formed an enlarged threaded lug 8.

Swiveled on bolt 7 is a plate 9, which acts as a washer between the eyes 6, and which extends beyond the eyes and is provided with an eye 10, whereby the tool may be hung above the wheel bench or stand in a shop.

The outer ends of arms 5, are split, and one portion bent out as at 11, whereby a jaw is formed for receiving one end of a half rim, as illustrated in Fig. 1, and in order that the half rim may be securely held, the outwardly bent portions are provided with threaded openings for receiving thumb screws 4, which as will be readily understood may be turned into engagement with the half rim for securely clamping the same within the jaw.

The arms 5 may be swung toward each other for drawing the rim, or may be separated for spreading the rim, as may be desired, and in order to accomplish the movement of the arms relatively to each other, I have provided an operating mechanism which comprises a screw 12 threaded at one end into the lug 8, and swiveled as at 13 at its opposite end in a follower 14 provided with oppositely extending arms 15, each of which is pivotally secured by means of rivets or pins 16 to the inner end of a link 17, the outer end of which is pivotally connected as at 18, to the outer end of one of the arms 5 near the jaw portion thereof.

The links 17, follower 14 and screw 12 lie in approximately the same plane, and by turning the screw 12 so as to bring the follower 14 toward lug 8, the outer ends of arms 5 will be drawn toward each other. In order to facilitate the turning of screw 12, I provide a hand wheel 19 which is keyed or otherwise secured to the screw near the follower 14, and which is provided with radially disposed arms or spokes 20 whereby the screw may be easily turned. The arms 20 are bent away from arms 15 on follower 14, so as to allow plenty of clearance for the hand of the operator in turning the screw.

The half rim shown in dotted lines in Fig. 1, is in an expanded or spread position, the normal position of the arms when first attached to a rim of standard size, being somewhat closer together than shown, so that the bolt may be turned in one direction or the other for drawing or spreading the rim as described.

The device may be constructed so as to be adjustable to various standard sizes of wheels, and to this end the links 17 may be extended, as shown in Fig. 3, and provided at their outer ends with a plurality of openings 21, for receiving the attaching means 18, which may be in the form of screws or bolts, so that the initial position of the

arms with relation to each other may be adjusted to the various standard sizes of rims.

Although I have described the preferred embodiment of my invention, I may desire 5 to make such change in the combination and arrangement of parts thereof as do not depart from the spirit of the invention and the scope of the appended claims.

I claim:—

- 10 1. A device of the class described, comprising a pair of curved arms having eyes formed at their inner ends, a bolt extending through said eyes for pivotally connecting said arms, said bolt having a lug formed on one end thereof, a plate swiveled on said bolt between said eyes, and extended beyond said eyes and formed with an eye, the outer ends of said arms being bifurcated and separated to form jaws, a screw extending through said lug, a follower swiveled on said screw, said follower formed with oppositely extending arms, links pivotally connected to said arms at one end, and at their opposite end each pivotally 25 connected to one of said curved arms near the outer end thereof, and a hand wheel secured to said screw for turning the same, said wheel provided with radially disposed spokes curved away from said follower for 30 providing a clearance for the hand of the operator.

- 35 2. A device of the class described comprising a pair of curved oppositely disposed arms pivotally connected together at one end, the outer ends of said arms being bifurcated and spread to form jaws, thumb screws carried by said jaws, links pivotally connected at their outer ends to said curved arms near said jaws, a movable element to 40 which the inner ends of said links are piv-

otally connected, and means for moving said element toward or away from the pivoted ends of the curved arms for separating or drawing said jaws together.

3. A rim spreader comprising a pair of 45 pivoted arms movable at one end toward and away from each other, and having jaws adapted to engage and hold a wheel rim at right angles to the plane of the arms whereby to leave the rim unobstructed, links pivotally 50 connected to said arms, a movable element to which the links are pivotally connected and means for moving said element whereby to adjust the jaws.

4. A rim spreader comprising a pair of 55 movable arms having jaws at one end adapted to engage and hold a rim at right angles to the plane of the arms, links pivotally connected to said arms, a follower pivotally connected to the links, a screw swiveled in 60 the follower, a bearing through which the screw is adapted to travel, and a hand wheel on the screw for turning the same.

5. An apparatus such as described comprising a yoke, a threaded bearing carried 65 by said yoke with the bore of the bearing in a plane parallel with that of the yoke, a bolt threaded in said bearing, and spreading arms between the ends of the yoke and operated by said bolt, all substantially as 70 described, whereby the apparatus may be applied to spread a rim segment with the yoke in a plane at right angles to that of the segment, leaving the segment unobstructed for the reception of spokes.

GEORGE E. POWERS.
